UNITED STATES PATENT OFFICE.

HENRY A. WEIHMAN, OF PHILADELPHIA, PENNSYLVANIA, ASSIGNOR TO SIMONS, BRO. & COMPANY, A CORPORATION OF PENNSYLVANIA.

DESIGN FOR A TEA-BALL.

No. 40,155.

Specification for Design.

Patented July 20, 1909.

Application filed February 23, 1909. Serial No. 479,667. Term of patent 7 years.

To all whom it may concern:

Be it known that I, HENRY A. WEIHMAN, a citizen of the United States, residing at Philadelphia, county of Philadelphia, and State of Pennsylvania, have invented a new, original, and ornamental Design for a Tea-Ball, of which the following is a specification, reference being had to the accompanying drawings, forming part thereof.

In the drawing, Figure 1 is a plan view, and

Fig. 2 is a side elevation of a tea ball, showing my new design.

I claim:

The ornamental design for a tea ball, as shown.

HENRY A. WEIHMAN.
